(57) **CLAIM**

The ornamental design for a fairing nose for motorcycles, as shown and described.

DESCRIPTION

FIG. 1 is a rear elevational view of a fairing nose for motorcycles showing our new design;

FIG. 2 is a left side elevational view thereof;

FIG. 3 is a right side elevational view thereof;

FIG. 4 is a top plan view thereof; and,

FIG. 5 is a front and left side perspective view thereof.

The ghosted or low contrasted portions of the motorcycle are provided for the purposes of illustrating environmental structure and do not form part of the claimed design.
